ATTORNEYS

UNITED STATES PATENT OFFICE.

NELLIE M. McCUALEY, OF KALISPELL, MONTANA.

SPRAYER.

1,140,177.

Specification of Letters Patent. Patented May 18, 1915.

Application filed October 14, 1914. Serial No. 866,598.

To all whom it may concern:

Be it known that I, Mrs. NELLIE M. McCUALEY, a citizen of the United States, residing at Kalispell, in the county of Flathead and State of Montana, have invented certain new and useful Improvements in Sprayers, of which the following is a specification.

This invention relates to sprayers and 10 more particularly to an improved device for spraying insecticides or other liquids.

One of the principal objects of the invention is to provide a spray which may utilize the water pressure in an ordinary garden 15 hose or one of a similar nature, in spraying the liquid without resulting in the mixture of the water with the liquid.

Another object of the invention is to provide a sprayer adapted to be placed in a pipe 20 or hose line and providing a collapsible container disposed in a body or cylinder and communicating with the spray nozzle, one end of the container acting as a piston and adapted to be forced along the cylinder by 25 water pressure behind in order to collapse the container, thus spraying the contents thereof out through the nozzle.

A further object is to provide a sprayer 30 of the class described which will be extremely simple, durable, efficient in operation and inexpensive to manufacture.

With these and other objects in view which will become apparent as the description proceeds, the invention resides in the 35 construction, combination and arrangement of parts, hereinafter more fully described and claimed, and illustrated in the accompanying drawing, in which like characters of reference indicate like parts throughout 40 the several figures, of which—

Figure 1 represents an elevational view partly in section of a sprayer constructed according to my invention. Fig. 2 represents a longitudinal central sectional view 45 taken therethrough. Fig. 3 represents an elevational view of the container removed from the device. Fig. 4 represents a transverse sectional view taken on the plane indicated by the line 4—4 of Fig. 2.

Referring more particularly to the drawing, the sprayer includes a cylinder 5, closed by a cap 6 at one end. The opposite end of the cylinder is externally threaded for receiving a flanged cover 7. Both the cap 6 and cover 7 are provided centrally with threaded nipples 8. A spraying nozzle 9 of

any well known and suitable construction may be threaded onto the nipple carried by cover 7, and a garden hose or similar water conduit (not shown) may be connected to 60 the opposite end of the cylinder by means of the nipple carried by cap 6.

The container comprises a flexible cylindrical body 10 which may be formed of any flexible material impervious to the fluid to 65 be sprayed. At one end of the body is disposed the flanged disk 11 to which the body is securely fastened. The opposite end of the body is provided with an externally threaded collar 12. As indicated in Fig. 2 70 the container is disposed longitudinally within the cylinder, and the collar 12 is threaded into the internally threaded outer end 13 of the cylinder. This disposes the disk 11 in the opposite end of the cylinder 75 adjacent cap 6, and the diameter of said disk is such that the disk fits snugly within the cylinder so as to form a piston capable of movement longitudinally of said cylinder.

Flexible container 10 is provided at suitably spaced points with encircling rings 14 secured to said container externally thereof and adapted to snugly fit within the cylinder 5. The rings are adapted to prevent collapse 85 of the container as the latter is being emptied.

The container may be filled with the desired liquid and placed within the cylinder, the latter of course being maintained in upright position during this process and 90 the cover 7 may be then threaded into place. The hose may be connected to the nipple carried by cap 6. When the water is turned on it will enter the cylinder behind the disk or piston 11, and the water pressure will 95 move said disk forwardly toward nozzle 9 against the internal pressure of the liquid contained in the collapsible body 10, thus forcing said liquid through the spraying nozzle. As the piston moves forwardly in 100 emptying the container the rings 14 will support the walls of body 10 and prevent them from collapsing, which action if not prevented might result in the blocking up or the cutting off of communication to the 105 spraying nozzle. The sprayer may be provided with a handle 15, if so desired.

Such a structure as I have provided may be quickly attached to or detached from an ordinary garden hose or a conduit of a similar nature and the water pressure in the 110 hose may be utilized in the manner set forth

in spraying the liquid from the container, without resulting in the mixture of the water with the spraying liquid.

Although I have described the preferred embodiment of my invention, I may desire to make such changes in the construction, combination and arrangement of parts thereof as do not depart from the spirit of the invention and the scope of the appended claims.

I claim:

1. A sprayer of the class described comprising a cylinder, a cap disposed on one end of said cylinder for closing the same, a threaded nipple carried by said cap, whereby the sprayer may be attached to a hose, a cover removably disposed upon the opposite end of the cylinder, a threaded nipple carried by said cover whereby a spraying nozzle may be connected with the sprayer, a container disposed within said cylinder and including a flexible body portion, a piston disposed at one end of said container and acting as a closure therefor, said piston being movable longitudinally of said cylinder, a collar carried by the opposite end of the body portion and connected to the cylinder internally thereof, and rings carried in spaced relation by said flexible body portion and fitting within said cylinder.

2. A device of the class described comprising a cylinder closed at one end, means at the closed end of the cylinder for connecting the same with a fluid conduit, a cover removably secured upon the opposite end of the cylinder, means carried by said cover for connection with a sprayer nozzle, a compressible container removably disposed within the cylinder, a piston carried

by one end of said container within the cylinder and adjacent the closed end thereof, means for removably disposing said container within the cylinder and means for preventing collapse of the container.

3. A device of the class described comprising a cylinder closed at one end, means at the closed end of the cylinder for connection with a fluid supply, a flexible container removably disposed within the cylinder, a piston secured to said container at one end within the cylinder and adapted to be actuated upon entrance of the fluid into the cylinder, for contracting the container, means for preventing collapse of the container and means for establishing communication with said container at the end opposite the piston, with a sprayer nozzle.

4. A device of the class described, comprising a cylinder, a flexible and collapsible container disposed therein and provided at one end with a ring snugly engaging within the cylinder, the end of the container adjacent the ring being open and being adapted to communicate with a sprayer nozzle, a piston connected to the opposite end of the container and closing the same and slidably engaging within the cylinder, rings carried by the container in spaced relation and engaged within the cylinder and adapted to prevent collapse of the container, and means whereby fluid may be forced into the cylinder against the piston whereby to collapse the container for ejecting the contents thereof.
